(57) **CLAIM**

The ornamental design for a surgical drain belt, as shown and described.

DESCRIPTION

FIG. 1 is a front perspective view of a surgical drain belt, according to a first embodiment of the invention;
FIG. 2 is a front view of the design of FIG. 1;
FIG. 3 is a back view of the design of FIG. 1;
FIG. 4 is a left side view of the design of FIG. 1;
FIG. 5 is a right side view of the design of FIG. 1;
FIG. 6 is a top view of the design of FIG. 1;
FIG. 7 is a bottom view of the design of FIG. 1;
FIG. 8 is a front perspective view of a surgical drain belt, according to a second embodiment of the invention;
FIG. 9 is a front view of the design of FIG. 8;
FIG. 10 is a back view of the design of FIG. 8;
FIG. 11 is a left side view of the design of FIG. 8;
FIG. 12 is a right side view of the design of FIG. 8;
FIG. 13 is a top view of the design of FIG. 8; and,
FIG. 14 is a bottom view of the design of FIG. 8.
Broken lines do not form part of the claimed design.
